UNITED STATES PATENT OFFICE.

JAMES A. PALMER, OF CRANSTON, RHODE ISLAND, ASSIGNOR TO PARKS BROS. & ROGERS, OF PROVIDENCE, RHODE ISLAND, A FIRM COMPOSED OF WILLIAM C. PARKS, OF BROOKLYN, NEW YORK, AND EVERETT I. ROGERS, OF PROVIDENCE, RHODE ISLAND.

DESIGN FOR A BUTTON-HEAD.

47,860.

Specification for Design.

Patented Sept. 21, 1915.

Application filed August 27, 1914. Serial No. 858,982. Term of patent 14 years.

To all whom it may concern:

Be it known that I, JAMES A. PALMER, a citizen of the United States, residing in the city of Cranston, in the county of Providence, in the State of Rhode Island, have invented a new, original, and ornamental Design for a Button-Head, of which the following is a specification, reference being had to the accompanying drawings, forming part thereof.

Figure 1 is a plan view of the head of a cuff button showing my new design. Fig. 2 is a sectional vertical view of the same.

I claim:

The ornamental design for a button head as shown.

JAMES A. PALMER.

Witnesses:

W. H. THURSTON,
J. H. THURSTON.
